UNITED STATES PATENT OFFICE.

JOHN WHITAKER, OF NORTH WALES, PENNSYLVANIA.

PRINTING DEVICE.

1,232,634.

Specification of Letters Patent. Patented July 10, 1917.

Application filed October 16, 1915. Serial No. 56,307.

To all whom it may concern:

Be it known that I, JOHN WHITAKER, a citizen of the United States, and a resident of North Wales, Montgomery county, Pennsylvania, have invented certain Improvements in Printing Devices, of which the following is a specification.

My invention relates to printing devices of the character employed for marking or printing checks, drafts and similar paper, with indicia, usually and preferably in indelible ink, representing the amount for which the check, draft &c., is drawn, or the amount which the value of the check or other paper should not exceed.

My invention comprises certain improvements in structures of this general character in which provision is made for relatively moving a printing drum or cylinder having lines of type with abrading or cutting faces, with respect to an impression platen which has an abrading or cutting face complementary to the type; means being provided to ink said type so that simultaneously with the cutting or abrading of the paper, ink will be applied thereto. While the printing drum or cylinder and platen may be relatively movable, one with respect to the other, the platen is preferably disposed in a fixed position; being carried by the base of the apparatus in the manner hereinafter described.

A further object of my invention is to provide means for imparting a sidewise or lateral movement to the printing cylinder within the frame in which it is mounted in order that the abrading or cutting type faces of the same may register with the complementary face of the impression platen.

Another feature of my invention consists of improved inking or ink distributing means for the type lines of the printing drum or cylinder in order that successive use of any one printing line will be immediately preceded by proper inking of the same without the necessity of rotating the printing cylinder to bring said type line into contact with the inking roller.

And a still further object of my invention is to provide a simple, strong and compact structure of few parts, easily operated, and not liable to get out of order.

These and other features of my invention are more fully described hereinafter, refer-

ence being had to the accompanying drawings, in which:

Figure 1, is a side elevation of a printing device of the type to which my invention has been applied;

Fig. 2, is an inverted plan view of the same;

Fig. 3, is a sectional view on the line III—III, Fig. 2; the machine being in the position shown in Fig. 1;

Fig. 4, is a similar sectional view showing the machine in the act of printing;

Fig. 5, is a sectional view of one end of the printing cylinder and its operating knob, on the line V—V, Fig. 2;

Figs. 6 and 7, are perspective views of the opposite ends of the printing cylinder or drum;

Fig. 8, is an enlarged view of a portion of one end of the printing drum disposed in a plane;

Fig. 9, is an enlarged view of a portion of a platen which I may employ;

Fig. 10, is an enlarged view of several of the types employed with such platen;

Fig. 11, is an enlarged sectional view of the type and platen, on the line XI—XI, Fig. 9;

Figs. 12 and 13, are views illustrating a modified form of platen and type, and

Fig. 14, is a cross sectional view on the line XIV—XIV, Fig. 12.

Referring to the drawings, 1 represents the frame of the printing device having a base 2 which is preferably integrally connected with said frame by a rear wall 3, while between the frame and base a slot or space 4 is provided for the insertion of checks or similar papers to be marked. The position of the checks with respect to the printing point may be determined by a gage 5.

Disposed within the frame 1 is a printing cylinder 6 having a series of type faces or type lines 7 longitudinally of the axis of the same; such type lines reading in various amounts to correspond with the value of a check or other paper, or amounts in excess of which the check should not be paid; which cylinder is secured to a shaft or spindle 8, having at the outer end an operating knob or wheel 9, whereby such cylinder can be set to any printing position desired.

This shaft or spindle 8 is mounted eccentrically in ball bearing rings 10 journaled in apertures 11 formed in the sides of the frame 1, and the printing drum or cylinder is under the control of a handle 12 suitably connected to said rings, as shown in Fig. 5. It will be understood therefore that movement of the handle to cause the cylinder to effect the printing operation will not only move the cylinder downwardly for contact of one of the type lines carried thereby with an impression platen 13 coöperating therewith, but will also impart a slight rotative movement to such printing drum due to its eccentric mounting; the position of the bearing rings 10 being such that proper contact of the line of type desired will be made with the platen 13 at the completion of the downward stroke of the operating handle.

For the purpose of returning the cylinder and its operating handle to the normal inactive position, I may provide a helically coiled spring 15 at one side of the frame, one end of which spring is connected to the printing cylinder, while its opposite end may be caught under a rod or bar 16 extending across the frame 1 at the rear of the same.

Carried by the base of the machine is a closure plate 17 which may be held in place by screws 18 and 19 whereby it may be adjustably mounted with respect to the active position of the drum or cylinder, and secured on the forward end of this closure plate is the impression platen 13, which is fixed in position. This platen carries on its face a plurality of arcuate or curvilinear grooves 13^a and 13^b lying in two positions, eccentrically disposed and crossing each other, whereby a plurality of piercing or cutting projections or points are produced; such projections or points coacting with the faces of the type which are complementally recessed to receive the projections or points of the platen when the printing drum is in the printing position.

The character of the impression platen and the printing type coacting therewith is substantially shown in Figs. 9 and 10. It will be understood, however, that the size of these parts as employed in the printing device forming the subject of my invention is such as to make an accurate showing of the same substantially impossible. The platen is made by grooving the surface of a suitable piece of metal by a suitable tool moving in curved paths, and the formation of a plurality of these curved grooves, or grooves following curved lines which lie in two directions, provides between them a multiplicity of small projections which are substantially in practice, points, lying in a plurality of arcuate or curvilinear lines eccentric to each other. The lines of type to coöperate with this platen may be recessed in any suitable

manner, as by a master platen; the recesses of the same registering with the points or projections of the platen and coacting therewith to actually pierce the check or other similar paper placed between the contacting faces. A modified form of platen and type is shown in Figs. 12 and 13.

The size of these points or projections may vary from side to side of the platen; the effect of which is to make fine apertures or holes in the paper of the check differing in size from top to bottom of the type impressions. The points of the platen and type pierce the paper and insure that the ink applied to the face of the paper by the type will be carried through the same.

As the platen is provided with cutting or piercing points or projections coöperating with complementally recessed type faces on the drum or cylinder, it is necessary to insure registry of the respective impression faces each time they are brought into engagement.

For this purpose, in the type of machine which I have illustrated, the printing drum has an endwise or lateral movement imparted thereto when swung by the operating handle to the operative position, which movement may be effected in the following manner:

With the form of machine illustrated, the platen is in relatively fixed position with respect to the printing cylinder, and one end of the latter is provided with projections or teeth 20 forming V-shaped grooves 21 between them, which grooves are beveled outwardly with respect to the cylinder and disposed tangentially to the axis of the cylinder. For coöperation with the grooves between these teeth, I provide a fixed projection 22 on the side wall of the frame which is in such position with respect to the printing cylinder as to be clear of the same when the latter is in the raised non-printing position free to rotate for setting purposes; such projection engaging one of the grooves 21 at the end of the cylinder upon depression of the latter by the operation of the handle 12.

As the printing drum or cylinder is lowered by the handle, the angular faces of one of the grooves 21 meets the projection 22, and continued downward movement of the printing drum insures that the projection will fully enter said groove, thereby holding the printing cylinder in a definite lateral position in order that the recesses of the line of type in printing position will exactly register with the cutting or piercing points or projections of the platen to insure a perfect impression. By this means, absolute registry is insured, and as the recesses of the several lines of the type will engage the points or projections of the impression platen at every operation of the machine,

there is no danger of damaging the said type lines.

The beveled grooves 21 between the teeth 20 at the end of the platen are set at such angles with respect to the axis of the cylinder and the plane of the end of the same that the projection 22 on the inner wall of the frame will fully engage both walls of such grooves, thereby insuring the maintenance of the cylinder in fixed position against longitudinal and rotative movement as it is being moved to and when in the printing position.

In order that the cylinder may be held laterally for proper engagement with the projection 22, I provide a spring stop finger 25 carried by the wall of the frame opposite said projection, which finger is adapted to engage notches or recesses 26 at the peripheral edge of the cylinder opposite the grooves 21; thereby facilitating the centering of the cylinder and the holding of the same when it has been moved by the knob or wheel 9 to the desired printing position. Accurate registry can not be insured by this stop finger, but the fixed projection engaging a groove at the opposite end of the cylinder or printing drum will insure such registry when the cylinder has been lowered by the handle for engagement with the platen in performing the printing operation.

For the purpose of inking the various type lines on the drum or cylinder, I provide a felt roll 30 mounted upon a rod or shaft 31 which may be supported by the bent arms of a spring carrier 32 supported by the rod 16. This spring frame is under tension to hold the roller against the type faces of the drum or cylinder at all times. It will be understood that such inking roll may at times provide an excessive amount of ink that will tend to smear or blur when making an impression on a check or other similar document, and for the purpose of avoiding such unsightly condition and for other reasons hereinafter mentioned, I provide means in the shape of a brush 35 designed to lie normally adjacent the type face in operative position, as shown in Fig. 3. When the cylinder is moved by the handle to bring a type face in contact with the check, means are provided whereby the brush will be swept across the face of the type to be put in action, thus removing the surplus ink and occupying a position forward of the cylinder during the printing operation as shown in Fig. 4; such brush returning to its normal position as soon as the handle is released. This arrangement accomplished two results; it removes any excess of ink that may result from the inking operation by the roller and at the same time it provides means whereby the active line of type in use may be re-inked at each

successive operation of the machine, so that should it be necessary or desirable to use the same line repeatedly, the brush will carry enough ink to insure proper inking of said line.

70

The brush 35 is carried by a suitable frame 36 journaled on the shaft or spindle 8, and this frame has a cam slot 37 at one end for engagement by a fixed pin 38 carried by the frame or casing 1; the relation being such that when the handle is moved the frame 36 will be actuated by said pin to lift the brush in front of the printing drum, as shown in Fig. 4. The outside of the casing is preferably provided with stops 39 and 39^a to limit the movement of the handle in both directions.

In order that the printing drum may be properly guided to and from the printing position when operated by the handle, I provide an arm 40 slidable with respect to the frame or casing, having an aperture 41 for the passage of the shaft or spindle 8 upon which said drum is mounted and carrying a rounded projection 42 adapted to a slot 43 in the side wall of the frame or casing. If desired, the projection may be of any suitable shape, preferably round. This arm carries the spring finger 25 which engages the notches 26 of the printing drum 95 and serves as the stop for the latter when it is in the printing position.

Externally of the frame 1, I provide an arm 44 which is mounted on the shaft or spindle 8 and is connected to the arm 40, 100 preferably by a screw 45 which enters the projection 42, and this arm 44 has at its upper end a guide or indicating finger 46 overlying the operating knob 9 which carries an index 47 of the type lines on the 105 printing drum. The relation of these parts is such that the printing drum will be held in proper position by the finger 25 to print the line indicated by the guide finger 46 on the index 47 of the operating knob 9.

110

It will be understood that the faces of the type of the printing drum when brought into contact with a check, draft or other paper to be marked and disposed over the platen, will cut or abrade the same, and that by reason of the inking of such type such ink will be deposited in the cut or abraded portions. In all instances the coating platen must be complementary to the type so that actual cutting or abrasion of the 120 paper is effected.

While I have described my present machine as having a platen with lines or rows of piercing points or cutting portions disposed in arcuate or curvilinear lines adapted to coöperate with lines or rows of recesses formed in the type and fitting such points or cutting portions and disposed in similar arcs, it will be understood that this arrangement may be reversed, and that the 130

125

type may be provided with sets or rows of 5
piercing points or cutting portions set in
arcuate or curvilinear lines for coöperation
with recesses formed in the platen and dis-
posed in the same arcuate or curvilinear
lines.

While I have shown specific embodiments
of portions or parts of the structure forming
the subject of my invention, it will be
10 understood that I do not wish to be limited
thereto, and my claims are intended to cover
such construction as well as any equivalent
thereof, singly or collectively performing the
same or an equivalent function.

15 I claim:

1. The combination in a printing appa-
ratus, of a platen having a series of pro-
jections, the projections on one side of the
20 platen being of a greater size than those on
the other side; a type cylinder having a
series of type faces thereon; eccentrics on
which the type cylinder is mounted; and
means for turning the eccentrics so that the
cylinder will approach the platen, the faces

of the type of the cylinder having indentations 25
corresponding to the projections of
the platen and so arranged that as the cylinder
approaches the platen the large projections
of the platen will engage the type 30
cylinder in advance of the smaller projec-
tions.

2. In a printing apparatus, the combina-
tion of a frame having a base; a platen car-
ried by said base, said platen having two
series of curved grooves, one series crossing 35
the other and forming diamond-shaped cut-
ting points, the points at one side of the
platen being smaller than those at the op-
posite side; a printing drum mounted in
said frame and having a plurality of lines 40
of type faces for engagement with said
platen, said type faces having recesses for
registry with the cutting points; and means
for bringing the type lines of the printing
drum into coöperating relation with the 45
platen.

JOHN WHITAKER.
